UNITED STATES PATENT OFFICE.

MERRITT A. KING AND CHARLES E. MULLIN, OF MOUNT PLEASANT,
PENNSYLVANIA.

DESIGN FOR A DISPLAY-STAND.

SPECIFICATION forming part of Design No. 25,923, dated August 11, 1896.

Application filed May 11, 1896. Serial No. 591,176. Term of patent 14 years.

To all whom it may concern:

Be it known that we, MERRITT A. KING and CHARLES E. MULLIN, of Mount Pleasant, in the county of Westmoreland and State of Pennsylvania, have invented and produced a new and original Design for a Display-Stand, of which the following is a full, clear, and exact description.

Reference is to be had to the accompanying drawings, forming a part of this specification, in which similar characters of reference indicate corresponding parts in both the figures.

Figure 1 is an elevation of a display-stand embodying our design; and Fig. 2 is a horizontal section on line 2 2, Fig. 1.

The design consists in its entirety of the novel base, the novel body, and the novel shelves within the body. Thus the base comprises the radially-disposed arms *a*, curved 20 downward at the ends at *a'*, and the ornamental ribs *a²* on top of the base at the center, the ribs running in the direction of the arms *a* and each presenting a substantially 25 triangular configuration, as seen in side view, the top edges having compound curves. The body *B* has a central standard *B'*, and the body is polygonal in horizontal section, the sides presenting a series of panels, each panel presenting an oblong central opening, 30 and a plane frame bordering and defining the opening, the plane frames being separated by intervening corner-posts that appear at the angles of the stand. The body further is surrounded by an ornamental railing *b*. The

shelves present each an open-work figure, 35 composed of radial arms *c*, having alternately curved parts *c'* and straight parts *c²*, (see Figs. 1 and 2,) and polygonal members *c³* of different sizes, arranged one within the other, as best seen in Fig. 2. 40

The leading feature of the design consists in the base, body, and shelves, the base presenting a plurality of radial arms having ornamental ribs at the center and ranging in the direction of said arms, the upper edges of 45 the ribs presenting compound curves, the body being polygonal, the sides of said body presenting a series of panels, each panel presenting an oblong central opening, and a plane frame bordering and defining the opening, the plane frames being separated by intervening corner-posts that appear at the angles of the stand, and the shelves presenting 50 an open-work figure composed of radial arms, alternately curved and straight, and 55 different-sized polygonal members arranged one within the other.

Another leading feature is the body having shelves of the configuration shown.

We claim—

The design for a display-stand herein shown and described.

MERRITT A. KING.
CHARLES E. MULLIN.
